AUTOGRAPHIC REGISTER

Alfred G. Traeder, Chicago, Ill.

Application November 8, 1933, Serial No. 697,093

9 Claims. (Cl. 282—21)

The invention relates to registers for handling business forms such as forms for recording sales and which may be presented for use and withdrawn for separation by tearing the extracted 5 form along a perforated line or on the fold between the continuous forms.

It is an object of the invention to provide a register for recording business transactions which will have practically universal application. At present there are two distinct types of receptacles in use. In one type, designed for counter use, the forms are ejected by rotating a registering cylinder, each revolution ejecting one form and automatically aligning the next form 15 in the machine. The ejected form must then be torn off by the operator so that two separate and distinct operations must be performed, one for the ejecting of the form and the other for separating the ejected form. The second type 20 of register is known as a finger pull type since the forms are withdrawn by the fingers of the operator and then separated by tearing as described. The invention concerns this latter type of machine which with the improved features 25 will operate with equal efficiency as a portable or stationary register even to replacing the crank operated type of register.

Another object is to provide an improved recording register of the type using the manifold 30 business forms which will properly align the original and duplicated forms with each other and which will have novel means for extracting the registered forms, the same requiring but one operation and automatically locating the next 35 succeeding forms in register.

More specifically an object of the invention is to provide novel release and extracting means for the forms operable by the fingers of the operator in the act of grasping the form to withdraw 40 the same from the machine.

Further objects of the invention reside in the provision of releasable registering pins which upon release allow the extraction of the registered form together with its duplicated copies, 45 automatically engaging with the next punched openings to align the succeeding forms and to register them in the machine, and the provision of an uninterrupted tearing edge on which the extracted form can be torn by an upward movement thereof.

With these and various other objects in view, the invention may consist of certain novel features of construction and operation as will be 50 more fully described and particularly pointed

out in the specification, drawing and claims appended hereto.

In the drawing which illustrates an embodiment of the device and wherein like reference characters are used to designate like parts— 5

Figure 1 is a perspective view of a register constructed in accordance with the present invention;

Figure 2 is a longitudinal vertical sectional view taken substantially on line 2—2 of Figure 1; 10

Figure 3 is a transverse sectional view taken substantially along line 3—3 of Figure 2;

Figure 4 is a fragmentary sectional view taken substantially along line 4—4 of Figure 3 showing the parts enlarged to more clearly illustrate 15 the details of the paper release;

Figure 5 is a fragmentary plan view of the paper releasing means showing the same in extracted position and modified by the addition of an adjustable tear-off edge. 20

The type of recording register selected for illustration of the preferred form of the invention consists of a frame of any suitable metal having a base 10, side members 11 and 12, a stationary end member 13 and an end closure 14 25 pivoted to the base at 15 and having formed integral therewith an upper transverse ledge 16 provided with depending side flanges 17 and which is bent at right angles to the end closure. The pivoted end 14 is adapted to be opened for 30 loading the machine, that is, locating a pack of manifold business forms 18 or other type of continuous forms within the frame, the same resting on the base 10.

An original form and copies to be duplicated 35 are located on the top plate 20 having side flanges 21 for fastening as by soldering or riveting to the side members 11 and 12, respectively, and a rounded rear edge 22 over which the forms pass in the operation of extracting the registered 40 form and locating the next succeeding form in registering position for use. Disposed over the front edge of the top plate 20 is a cover member 23 pivoted at 24 and having its free end bent as at 25 to provide a spring lock, holding the 45 cover member in operative position in contact with the projecting stops 26 (Figure 5) located to the extreme outer edges of the top plate. The front end of the top plate is provided with a pair of spaced openings for receiving the registering pins 30 carried by the strip 31 of spring metal which is soldered or otherwise secured as at 32 to the undersurface of the top plate 20. The metal strip 31 resiliently forces the registering pins up through the openings therefor 50

55

in the top plate and also through the openings 33 in the forms 18 when aligned therewith. The frame 28 provides a tension and paper lock by applying a slight pressure on the edges of the form when the finger or wrist of the operator is laid thereon. The rear end of the frame is pivoted at 34 to the transverse member 35 secured in any suitable manner to the side members 11 and 12 of the register. To permit passage of the forms between the top plate 29 and the tension paper lock 28 its supporting member 35 is located slightly above the top plate which together with the pivot 34 is adapted to be covered by flange 16 of the end closure 14. With the flange 16 overlying the pivoted end of the frame 28 the joint 34 is out of sight, thus adding to the pleasing appearance of the register. The free end of the frame is held down in contact with the paper by the cover member 23 although having limited movement to free the tension on the forms when it is desired to extract the same. This end of the frame 28 is also provided with a pair of openings 36 in alignment with those in the top plate for receiving the ends of the registering pins 30 projecting above the registered forms 18. Registers of the type disclosed render an original form in addition to one or more duplicated copies and for the purpose it is necessary to provide a sheet of carbon paper, which in the type of machine disclosed passes over the top plate transversely, being located between the forms thereon which travel over the top plate longitudinally. The carbon paper is taken from a roll located in the receptacle 38 provided therefor and which consists of an arcuate bottom plate 39, end plates 40, and a top closure plate 41, resiliently held in closed position to provide the necessary tension on the carbon strip. The receptacle 38 is secured to the side member 11 in spaced relation to provide finger grasping means facilitating in lifting and carrying of the register by one hand of the operator. The fingers of the operator are located under the arcuate bottom member 39 while the thumb is located over the closure to engage a portion of the frame 28, thereby holding the forms against movement. This leaves the other hand of the operator free for recording a business transaction and for extracting the form from the machine in the manner which will now be described.

50 The invention provides a delivery slide in the form of a member 42 which extends transversely of the register, having downwardly turned ends bent back upon the member but spaced therefrom to support the shaft 43, Figure 5. The delivery slide is supported for slidable movement by a pair of rods 44 secured to the respective ends thereof and supported from the undersurface of the top plate 29 by brackets 45. Stops 46 are provided adjacent the inner ends of the rods which are resiliently biased in a direction to hold the member 42 against the register by coil springs 47. The position of the stops 46 limits the travel of the delivery slide 42 which is immediately returned to its position as shown in Figure 1 by the coil springs 47. The ends of the business forms 18 extend between member 42 and the shaft 43 so that the ends of the forms are in a position to be held to slide 42 by the operator in the act of grasping the form to withdraw the same from the machine. The invention makes use of this act to automatically withdraw the registering pins through the provision of the finger release pivotally mounted on shaft 43 and thereby carried by the delivery slide 42. End 50 of the finger release 75 is located under the delivery slide and operates

to confine the ends of the forms therebetween, as shown in Figure 4. The other end 51 extends over the strip of spring metal 31 contacting the strip and being operative to depress the strip to withdraw the pins when the finger release is held by the operator to grasp the ends of the business forms.

As will be seen the operation of holding the forms to the delivery slide and of depressing the registering pins is accomplished by one act of the operator, whereupon the extraction of the forms is initiated by outward movement of the slide and which continues until the stops 46 limit further movement in an outward direction. The delivery slide is immediately returned to position requiring only that the operator release the slide and the finger release 50 which although interrupting the act of extracting the form takes place almost simultaneously therewith as the operator maintains his thumb and finger in the same position to grip the projected end of the forms and thus continue their movement, which movement continues until the next openings 33 are located in alignment with the registering pins 30. As the pins are free to travel upwardly they are located in the aligned openings, registering the forms in the machine. The member 42 also provides an uninterrupted tearing edge for severing the extracted form. This operation requires that the operator pull upwardly on the extracted form, holding the same against the outer edge provided by the delivery slide and by applying further tension tearing of the forms along this edge is effected. This operation is accomplished almost simultaneously with the act of withdrawing the form and has an added advantage that the tear-off edge may be adjustable as shown in Figure 4 to accommodate various forms. The adjustable edge requires the addition to the delivery slide of a strip 52 co-extensive in length with that of the slide and secured thereto in adjusted position by set screws 53.

I claim:

1. In an autographic register, a substantially flat writing surface, registering means associated therewith for holding a form in registered position on the writing surface, a delivery slide having limited movement with respect to said surface for partially extracting said form, and a member carried by said slide for releasing the registering means to permit extraction of said form.

2. In an autographic register, a substantially flat writing surface, registering means associated therewith for holding a form in registered position on the writing surface, a delivery slide associated with said surface, means mounting said slide for movement with respect to said surface, said slide being operative to partially extract said form, and a member carried by said slide for holding a form to the slide and for simultaneously releasing the registering pins to permit extraction of the form.

3. An autographic register comprising a casing having a substantially flat upper surface, said casing being adapted to receive a plurality of connected forms for location successively on said surface, registering means at one end of the surface, said means being adapted to engage with openings in a form to register the same on said surface, a delivery slide, and a release member carried by the slide and operative to release the registering means, said slide also providing an uninterrupted tearing edge for the extracted forms.

4. An autographic register comprising a casing having a substantially flat upper surface, said casing being adapted to receive a plurality of connected forms for location successively on said surface, registering means at one end of the surface, said means being adapted to engage with openings in a form to register the same on said surface, a delivery slide, and a release member carried by the slide and operative to hold the forms to the slide and simultaneously release the registering means to permit extraction of the form, the edge of said slide providing an uninterrupted tearing edge for the extracted form.

5. In an autographic register of the type using continuous forms, a substantially flat writing surface, registering means for holding and registering the form thereon, said means including a plurality of pins projecting within openings in the form and being operable to permit extraction of the form, a delivery slide supported for slidable movement and adapted to have limited outward movement from said surface, a release member carried by said slide and associated with said registering pins, said member and slide when gripped by the operator holding the form therebetween and said member automatically releasing the registering pins to permit extraction of the form.

6. In an autographic register, a substantially flat writing surface, registering pins associated therewith for holding a form in registered position on the writing surface, a delivery slide having limited slidable movement with respect to said surface for partially extracting said form, a release member carried by said slide and having operative connection with the registering pins, the free edge of said form being adapted to be positioned between the delivery slide and release member, whereby said form is partially extracted by the act of the operator in grasping the slide and member and withdrawing the slide, said operation initially actuating the member to cause release of the registering pins, and said pins being free to again function as registering means upon release of the delivery slide at the end of the extracting operation.

7. In an autographic register, a substantially

flat writing surface, registering pins associated therewith for holding a form in registered position on the writing surface, a delivery slide having limited slidable movement with respect to said surface for partially extracting said form, a release member carried by said slide and having operative connection with the registering pins, said member being operative to hold the form to the slide and to simultaneously release the registering pins to permit extraction of the form by the outward movement of the delivery slide, and said pins being free to perform their registering function upon release of the delivery slide.

8. In an autographic register, a substantially flat writing surface, registering pins associated therewith for holding a form in registered position on the writing surface, a delivery slide having limited slidable movement with respect to said surface for partially extracting said form, a release member carried by said slide and having operative connection with the registering pins, said member being operative to hold the form to the slide and to simultaneously release the registering pins to permit extraction of the form by the outward movement of the delivery slide, resilient means for automatically returning the delivery slide to initial position upon release thereof, and said pins being free to perform their registering function upon said release of the delivery slide.

9. In an autographic register of the type using continuous forms, a substantially flat writing surface, registering means associated therewith for holding a form in registering position on the writing surface, a delivery slide having limited slidable movement with respect to said surface for partially extracting said form, a release member carried by said slide and having operative connection with the registering pins throughout the extent of movement of said slide, the free edge of said form being adapted to be located between the delivery slide and member and whereby the same may be grasped therebetween for partially extracting said form, and means for automatically returning the delivery slide to initial position upon release thereof.

ALFRED G. TRAEDER.
